MAX M. COHN, OF PIEDMONT, CALIFORNIA

MEANS FOR DISPENSING PAPER TOWELS.

1,126,400.

Specification of Letters Patent.

Patented Jan. 26, 1915.

Application filed December 15, 1913. Serial No. 806,752.

To all whom it may concern:

Be it known that I, MAX M. COHN, a citizen of the United States, residing at Piedmont, in the county of Alameda and State 5 of California, have invented new and useful Improvements in Means for Dispensing Paper Towels, of which the following is a specification.

This invention relates to paper towels and 10 pertains especially to means and a mode of dispensing the towels so that only one can be withdrawn at a time.

While there are various ways for carrying out the invention, I have herein shown 15 a simple and preferred method of practising the same.

The invention consists of the parts and the combination and construction of parts as hereinafter more fully described and 20 claimed, having reference to the accompanying drawings, in which—

Figure 1 is a perspective view of the device. Fig. 2 is a detail section of the container showing the paper towels in place.

25 A represents a sheet of paper which is of desired quality and size, according to the use to which it is to be put. As this invention has been designed particularly as applied to paper towels, the paper must be 30 absorptive and the sheets are of considerable size. This sheet A in the form here shown is folded once upon itself to provide a shorter underneath flap section 2; the folds of all the sheets being uniform with 35 one folded sheet lying on top of the other in the stack and all contained in a suitable container B. This container B is of suitable material such as metal and may have a drop front closure 3 through which a stack 40 of folded sheets may be inserted. The container has a bottom slot 4, the length of which corresponds to the full width of a towel and the width of which slot is sufficient to allow the flap 2 of the bottom-most 45 sheet in the stack to fall through and project to form a finger hold and enable the towel to be withdrawn. The front wall of the slot 4, or that portion 5 of the bottom of the receptacle B is dropped down at an 50 incline at the ends and preferably is cut away in the middle as shown at 6, so that at this middle portion 6 the folded edge formed by the fold of the flap 2 is exposed and unsupported; the stack on this side being supported by the downwardly inclined

ends 5, thereby facilitating the withdrawal of the single sheets.

The portion 7 of the bottom of the container opposite the inclined portions 5 has its edge adjacent slot 4 turned upwardly in 60 the form of a bead or smooth rounded portion 8 over which it is comparatively easy to draw the body of the sheet when the flap 2 is pulled down.

Each sheet A is so folded that the body 65 of a sheet is of the full width of the container B, so that when a flap 2 is projecting from slot 4 there is no portion of any sheet above the bottom-most that is visible or accessible. The consequence of so folding a 70 sheet that it will have a comparatively wide section the full width of the container, is very important because it forbids any likelihood of more than one towel, or one sheet being withdrawn at a time, which is quite 75 important from the standpoint of economy.

The sheets when stacked have their marginal fold 2 undermost and overlying the wider section of the sheet; this wider section having an area substantially equal to 80 the cross area of the stack. By having the bottom portion 5 dropped down and inclined in the manner shown and in a plane below or intersected by the plane of the opposite portion 7, each marginal fold 2 is adapted 85 to be projected through the slot as the bottom-most sheets are successively withdrawn.

Having thus described my invention, what I claim and desire to secure by Letters Patent is—

1. A container for sheets having folded flaps consisting of a casing having a slot in its bottom, one of the edges of the bottom which said slot forms being curled upwardly and over upon itself to form a rounded bearing which projects above the upper face of the bottom and upon which the body of the sheet is adapted to rest, and ride upon withdrawal of the sheet, the part of the bottom on the other side of the slot being curved 100 downwardly to have a convex upper face upon which the flap of the sheet is adapted to rest, the free edge portion of the said curved part of the bottom having an opening to provide means to enable the folded 105 part of the sheet to be gripped with the hand of the user.

2. A container for sheets having folded flaps consisting of a casing having a slot in its bottom, a rounded bearing at the inner 110

12
side of the slot projecting upwardly from the upper face of the bottom and upon which the body of the sheet is adapted to rest, and ride upon withdrawal of the sheet, 5 the bottom on the outer side of the slot being extended downwardly at an incline to form a support for the folded part of the sheet, which support projects for a distance below the bottom of the casing to enable the

folded part of the sheet to be positively supported and be readily accessible to the user. 10

In testimony whereof I have hereunto set my hand in the presence of two subscribing witnesses.

MAX M. COHN.
